CLAIM

The ornamental design for a bottle body or similar article, as shown and described.

DESCRIPTION

FIG. 1 shows a front elevational view of a bottle body or similar article.

FIG. 2 is a sectional view of the bottle body taken on the line 2—2 of FIG. 1.

The left side, right side and back elevational views are identical to the shown elevational view.

The broken lines showing a bottle finish are for the purpose of illustrating environmental use only.
